WARNING SIGNAL FOR A GRADE CROSSING

Frank A. Marik, 1099 E. Washington Ave.,
El Cajon, Calif.

Filed Oct. 16, 1959, Ser. No. 57,962

Term of patent 7 years

(Cl. D72—1)

FIG. 1.

FIG. 2.

Figure 1 is a front elevational view of a warning signal, for a grade crossing, showing my new design; and

Figure 2 is a side elevational view of the same.

Figure 1 of the drawing is shaded to show contrast.

I claim:

The ornamental design for a warning signal for a grade crossing, as shown and described.
